FIG. 5.

UNITED STATES PATENT OFFICE.

LOUIS C. BITZER, OF CHESWICK, PENNSYLVANIA, ASSIGNOR TO THE RED RAVEN CORPORATION, A CORPORATION OF PENNSYLVANIA.

CONTAINER.

Application filed March 24, 1926. Serial No. 96,991.

This invention relates to containers or cartons adapted to hold articles of merchandise for shipment, display or the like.

An object of this invention is to provide 5 an improved form of device of the type set forth having a simple and rugged construction which will be cheap and easy to manufacture.

This and other objects which will be apparent to those skilled in this particular art 10 are accomplished by means of this invention, one embodiment of which is shown in the accompanying drawings, in which Figure 1 is a perspective view of a container 15 constructed in accordance with one form of this invention. Figs. 2 and 3 are similar views showing the container open and Figs. 20 4 and 5 are transverse sectional views through the central part of the container. The particular embodiment of this invention 25 which has been chosen for the purposes of illustration is adapted to contain such merchandise as ginger ale bottles or the like, but it will be apparent that the invention is adaptable to all forms of containers.

The illustrated embodiment consists of a container including back and end walls of the usual form. The front wall is cut away or the container is so formed that the front 30 wall does not extend entirely across the front of the container so that when the container is open the contents thereof are visible through the open portion of the front wall. A lid is hinged to the back wall and 35 an extension or closure is formed on the lid for covering the open portion of the front wall when the lid is closed. A separate device such as a partition is adapted to be inserted along the front of the container and 40 this partition is provided with a flap which falls outwardly and downwardly upon opening of the container so as to expose the contents through the open portion. The face of the flap which is thus exposed to view bears 45 a legend such as directions for the use of the merchandise, trademarks, advertising matter or the like.

As illustrated, the container 5 has a back wall 6 and end walls 7. The front portions 50 of each end wall are bent inwardly to form wings 8 of such construction and arrangement as to constitute the side portions of a front wall, the center part of which is open or cut away to provide an opening 9. The 55 wings 8 of the side walls are held in position

and the various parts of the entire box are held in assembled relation by an upwardly extending flap 10 formed on the bottom 11 of the container which embraces the lower portions of the wings 8 and extends across 60 the bottom of the open space 9 therebetween. Any desired means, such as securing strips 12 of paper or other material, may be employed for holding the parts in their assembled relation.

A separable partition 13 has a lower supporting portion 14 adapted to be inserted within the flap 10 enclosing the bottom front of the container, and a flap 15 is hinged to the supporting portion for closing the opening 9 when in upright position. When the container is open the flap is adapted to fall downwardly and outwardly as shown in Fig. 3 and the exposed face of the flap when in this position is provided with any desired 75 form of legend such as directions for the use of the merchandise, advertising matter or the like.

The container is closed and the legend bearing flap 15 is held in upright position, 80 see Fig. 2, by an extension or closure flap 16 formed on an adjacent portion of the container such as, for example, the front edge of the hinged cover 17. With the construction illustrated it will be apparent that 85 when the lid is closed, after positioning the legend bearing flap in its upright position across the opening 9, the extension 16 will cover the open portion 9 and cooperate with the flap 10 forming the base of the front 90 wall to close the container, and the container can be sealed by a sealing strip 18 extending along the joint formed by the meeting edges of the extension 16 and the wall base 10. A seal breaking string 19 can be positioned 95 along the joint beneath the sealing strip and its end securely held by a paper seal 20 which may bear a trademark or any other desired configuration.

Upon opening the container the seal is 100 broken by pulling the string 19. The closure flap 16 can then be opened whereupon the legend bearing flap 15 falls outwardly to the position shown in Fig. 3 so as to expose the contents of the container and at the 105 same time render directions or other reading matter visible.

It will be apparent that the use of the terms side walls, front walls, top, bottom, etc. in the present description is applied to 110

the illustrated embodiment of the present invention. Obviously, these terms are not used in a limiting sense but are intended to be merely descriptive of the illustrated embodiment.

What I claim as new and desire to secure by Letters Patent is:

1. The combination in a container for articles of merchandise, of an opening formed in one wall, an extension formed on the top of the container for covering said opening when the container is closed, a removable partition adapted to extend across said opening beneath said extension and provided with a legend bearing flap hinged thereto so as to fall into such a position upon opening the container as to expose the interior of the container and render the legend bearing face of the flap visible.
2. The combination in a container for articles of merchandise of a back wall having a lid hinged thereto, side walls, a bottom

provided with an upwardly extending flap forming the lower portion of a front wall, an extension formed on said lid and adapted to cooperate with said flap for closing the front wall and a partition adapted to be inserted within said flap provided with a legend bearing section adapted to fall into legend displaying position upon opening said container.

3. The combination in a container having side and back walls, of a front wall having a portion thereof cut away, a partition placed within said front wall and extending across the opening therein, a lid having an extension for covering said opening when said lid is closed and a flap hinged to said partition for swinging outwardly upon opening of said lid.

In testimony whereof, I have hereunto subscribed my name this 18th day of March, 1926.

LOUIS C. BITZER.
